STEAM TRAP

Ronald D. Schlesch, Three Rivers, Mich., assignor to Armstrong Machine Works, Three Rivers, Mich.

Filed Nov. 27, 1973, Ser. No. 419,437

Term of patent 14 years

Int. Cl. D23—01

U.S. Cl. D23—1

FIG. 1 is a front elevational view of a steam trap showing my new design;

FIG. 2 is a rear elevational view thereof;

FIG. 3 is a top view thereof;

FIG. 4 is a bottom view thereof; and

FIG. 5 is a side elevational view thereof, the opposite side being a mirror image thereof.

I claim:

The ornamental design for a steam trap, as shown and described.
